UNITED STATES PATENT OFFICE.

CHARLES H. KNELL, OF VERONA, PENNSYLVANIA, ASSIGNOR TO VERONA TOOL WORKS, OF PITTSBURGH, PENNSYLVANIA, A CORPORATION OF PENNSYLVANIA.

ANTICREEPING DEVICE FOR RAILWAY RAILS.

Application filed June 13, 1923. Serial No. 645,085.

To all whom it may concern:

Be it known that I, CHARLES H. KNELL, a citizen of the United States, residing at Verona, in the county of Allegheny and 5 State of Pennsylvania, have invented a new and useful Improvement in Anticreeping Devices for Railway Rails, of which the following is a full, clear, and exact description.

The present invention relates broadly to 10 rail fastenings or rail anchors, and more particularly to fastenings of the type usually referred to in the art as anticreepers for preventing longitudinal creeping of the rails to which they are applied.

15 From a manufacturing standpoint it is highly desirable to provide an anti-creep constructed of stock adapted to be easily produced in quantities and easily formed into the desired shape. To this end, rail anchors in accordance with the present invention are preferably formed of flat or substantially flat strips of metal, whereby they may be easily bent to shape. Such a construction is disclosed in my Reissue 20 Patent No. 15,470 of October 17, 1922. In that construction, however, when the key is driven into place, the body of the anchor tends to move away from the base of the rail and materially decreases the effective grip 25 between the anchor and the rail base flange. In accordance with the present invention, there is provided an anchor which is adapted to be drawn upwardly when the key is driven downwardly into position.

30 35 In the patent of Peters No. 1,435,731 of November 14, 1922, and more particularly in Fig. 5 thereof, there is disclosed generally such a construction. In that form of anchor, however, there is not utilized a flat bar and a very considerable portion of the load is 40 imposed upon the head, tending to bend the same outwardly and release the rail to such an extent that unless the anchor is exceptionally heavy, the main body thereof tends 45 to move away from the base of the rail as the key is driven home. Furthermore, however, it is very desirable to provide means for effectively holding the key in position to counteract the tendency thereof to become 50 loose under the constant hammering of the wheels on the track.

In accordance with the present invention, there is provided an anti-creep producing the desired characteristics referred to and

of such construction that the key is effectively held in position with the body of the anchor against the base of the rail. 55

In the accompanying drawings, there are shown, for purposes of illustration only, certain embodiments of the present invention, 60 it being understood that the drawings do not define the limits of my invention, as changes may obviously be made in the construction, as disclosed therein, without departing from the spirit of the invention or 65 scope of my broader claims.

In the drawings, Figure 1 illustrates in transverse section a standard rail having an anti-creep constructed in accordance with the present invention applied thereto. 70

Figure 2 is a top plan view of the anti-creep illustrated in Fig. 1 removed from the rail and with the key removed from position.

Fig. 3 is a transverse sectional view 75 through the key.

Fig. 4 is a view corresponding to Fig. 1 illustrating a slightly modified form of the invention.

Fig. 5 is a top plan view of the anti-creep illustrated in Fig. 4. 80

Fig. 6 is a view similar to Figs. 1 and 4, illustrating still another embodiment of the invention.

Fig. 7 is a top plan view of the anti-creep illustrated in Fig. 6, and 85

Figures 8 and 9 are detailed views illustrating the construction of the key for the anti-creep shown in Figures 4 and 7.

In Figures 1 to 3, there is illustrated the preferred embodiment of the present invention. In accordance with the invention, 90

there is provided an anti-creep constructed of a substantially flat strip of metal bent edgewise upon itself, adjacent one end, to form a loop 2 for the reception of one edge of the rail base flange of a standard rail 3. The main body of the anti-creep extends transversely beneath the base of the rail, with its greatest dimension in a vertical direction, whereby an efficient tie abutting surface is presented. Adjacent its opposite end, the body of the anti-creep is bent slightly in an edgewise direction to bring a portion thereof into a plane above the plane of the rail base. This end is then bent flatwise upon itself to provide a loop 4 having a key abutting shoulder 5. It will be noted that 105

this shoulder, due to the upward bending of one end of the anti-creepér, extends transversely of and above and below the plane of the rail base, whereby an effective abutting 5 surface in the plane of the rail base is insured.

In accordance with the present invention, the flatwise bend for forming the loop 4 is so made that the key abutting shoulder 5 extends at an incline to the vertical, this inclination preferably being upwardly and inwardly. The loop 4 is adapted to receive a key 6, which is driven vertically into position between the edge of the rail base and 10 the shoulder 5. The key 6 is preferably tapered or wedge-shaped, whereby as it is driven into position a wedging action is exerted on the rail base tending to draw the body of the anti-creepér laterally for effectively gripping one edge of the rail base 15 in the loop 2. At the same time, due to the inclination of the rail abutting shoulder 5, the entire body of the anti-creepér is swung about the edge of the rail located in the loop 20 2 as a fulcrum, whereby the main body is drawn upwardly into tight engagement with the base of the rail. This places the body of the anti-creepér under tension, tending to bend the same, but due to the disposition of 25 its mass, it will be apparent that a maximum strength against such bending action is insured.

It has been found highly desirable in order to prevent release of the key from its 30 tight position, to provide the same with serrations or teeth 7 on the edge which engages the shoulder 5. These teeth bite tightly into the metal constituting the shoulder and prevent downward movement of the anti-creepér away from the base of the rail, and 35 at the same time, prevent the key from working upwardly.

While the edge of the key which engages the edge of the rail base flange may be of 40 any suitable construction, I have found it highly desirable to provide a key having the intermediate portion 8 thereof cut away to provide line contacts 9 for effectively biting into the edge of the rail.

In Figures 4 and 5 there is illustrated a 45 modification of the present invention, in which a rail anti-creepér is constructed of substantially flat material having an edge-wise bend adjacent one end thereof, to form a rail base flange receiving loop 2^a. Intermediate its ends, the body of the anti-creepér is bent through substantially 90 degrees. This end is then bent flatwise upon itself to 50 form a loop 4^a and to provide a key abutting shoulder 5^a. In order to receive the lower end of the key, the anti-creepér is formed with an opening 10. One side of this opening is in line with the shoulder 5^a, and both the shoulder 5^a and this edge of the opening 55 are inclined upwardly and inwardly,

whereby when the key 6^a is driven into position, the anti-creepér will be drawn laterally and upwardly, as before pointed out.

In Figures 6 and 7 there is illustrated still another embodiment of the invention, in 70 which the loop 2^b is formed by a flatwise bend and the tie abutment is secured by striking downwardly a portion 11. The key receiving end of the anti-creepér is constructed as before described in connection 75 with Figures 4 and 5 and the same reference characters have been used to indicate the different parts thereof. In both of these forms of the invention, the key is formed with teeth 7^a tending to prevent the key 80 from working loose under the hammering action of the wheels on the track.

The advantages of the present invention arise from the provision of an anti-creepér which may be easily and inexpensively 85 manufactured and in which an inclined key abutting shoulder is formed by bending a portion of the body of the anti-creepér, whereby when the key is driven into position distortion of the anti-creepér is prevented and a laterally and upwardly movement thereof insured. 90

I claim:

1. In a rail anchor, a body of substantially flat material bent edgewise upon itself at one end to form a rail base flange receiving loop, and bent flatwise upon itself at the other end to form a key abutting shoulder, said shoulder being inclined upwardly and inwardly, and a key adapted to be driven between the opposite edge of the rail base and said shoulder, substantially as described. 95

2. In a rail anchor, a body of substantially flat material bent to form a rail base flange receiving loop at one end and bent upwardly at its opposite end to form a key abutting shoulder, a portion of which lies above the plane of the rail base, said shoulder being inclined upwardly and inwardly, and a key adapted to be driven between an edge of the rail base and said shoulder, substantially as described. 100 110

3. In a rail anchor, a body of substantially flat material, bent to form a rail base flange receiving loop at one end, and bent flatwise at its opposite end to form a key abutting shoulder, said shoulder being inclined upwardly and inwardly, and a key adapted to be driven between one edge of the rail base flange and the shoulder, substantially as described. 115 120

4. An anti-creepér for rails comprising a member adapted to extend underneath the rail base and having loops at its opposite ends, one of the loops extending at an angle to the other loop and having a key receiving opening formed with an upwardly and inwardly inclined key abutting shoulder, and a key adapted to be driven in the opening 125 130

and engage the edge of the rail flange, substantially as described.

5. An anti-creeper for rails comprising a member adapted to extend underneath the rail base and having one end bent upwardly to engage the rail base flange, and having the other end bent upwardly and laterally at an angle to the body of the material to form a key socket having an upwardly and 10 inwardly inclined key abutting shoulder, substantially as described.

6. An anti-creeper for rails comprising a member adapted to extend underneath the rail base and having one end bent upwardly 15 to engage the rail base flange, and having the other end bent upwardly and laterally at an angle to the body of the material to form a key socket having an upwardly and

inwardly inclined key abutting shoulder, and a key adapted to engage said shoulder 20 to prevent accidental release thereof, substantially as described.

7. An anti-creeper for rails comprising a metal bar having one end portion bent up to form a loop to engage the rail base and the other end portion bent sidewise to form a key receiving loop having an upwardly and 25 inwardly inclined key abutting shoulder, said loop extending upwardly, opposite to the edge of the rail base, and a key adapted 30 to co-operate with said shoulder, said key having means to prevent accidental release thereof, substantially as described.

In testimony whereof I have hereunto set my hand.

CHARLES H. KNELL.
